DESIGN FOR A LIP STICK CASE

Charles S. Gage, Tarrytown, N. Y., assignor to
Lentheric Incorporated, New York, N. Y., a
corporation of New York

Application February 28, 1934, Serial No. 50,900

Term of patent 14 years

To all whom it may concern:

Be it known that I, CHARLES S. GAGE, a citizen of the United States, residing at Tarrytown, in the county of Westchester and State of New York, have invented a new, original, and ornamental Design for a Lipstick Case, of which the following is a specification, reference being had to the accompanying drawing, forming part thereof:

Figure 1 is a top plan view of a lipstick case showing my new design; and

Figure 2 is a side elevation thereof.

The white stripes on the black areas and the

nonhorizontal black lines on the white areas indicate high lights, and are not a part of the design.

The annular area bounded by the horizontal lines near the top of Figure 2 is of a lustrous metallic color.

I claim:

The ornamental design for a lipstick case substantially as shown and described.

In witness whereof I affix my signature.

CHARLES S. GAGE.
